APPARATUS FOR ROLLING FOOTWEAR

Herbert R. Polleys, New Haven, Conn., assignor to United States Rubber Products, Inc., New York, N. Y., a corporation of Delaware

Application August 7, 1936, Serial No. 94,735

8 Claims. (Cl. 12—1)

This invention relates to an improved apparatus for rolling the sole or bottom portion of footwear and particularly to the combination of a conveyor and an adjustable rolling mechanism 5 for rolling the footwear while carried by the conveyor.

In the manufacture of rubber footwear articles, the sole or bottom portion is built up of a plurality of parts on a last carried by a conveyor 10 and the adhering parts are compacted together by one or more sets of rollers during their travel on the conveyor. In addition to the building up of the parts, certain other operations are performed on the footwear before and after the sole portions 15 are rolled. The amount of working space required to perform these operations before and after the footwear article reaches the rolls varies with different types of footwear.

Heretofore the pressing rolls have been permanently fixed at a point on the path of the conveyor which was suitable for a given type of footwear. In cases where a different location of the rolls was required to provide the necessary working spaces for other types it was necessary to 25 spend time and money in altering the apparatus or make the conveyor sufficiently long to take care of all types of footwear.

In the present invention the rolling mechanism is movably mounted upon a track extending substantially parallel with the direction of movement of the conveyor and the mechanism is adapted to be secured to the track at different points along the path of the conveyor in order to provide the necessary space required for performing the various operations either before or after the footwear article has been rolled, and thereby make it possible to employ a shorter conveyor or utilize the working space along the conveyor more efficiently for the manufacture of 40 various types of footwear. The rollers are adapted to be moved towards and away from the conveyor in order that footwear of different heights may be operated upon and a stop mechanism is provided for protecting the apparatus 45 against damage in the event the rollers are placed too near the traveling conveyor.

The foregoing objects and other features and advantages of this invention will be more clearly understood by referring to the following specification and the accompanying drawings in which:

Fig. 1 is a front end elevational view of an apparatus embodying this invention;

Fig. 2 is a side elevational view taken from the 55 left in reference to Fig. 1 and showing the foot-

wear article as having passed the rolling mechanism;

Fig. 3 is a top plan view of the apparatus showing the footwear article before arriving at the pressing rolls;

Fig. 4 illustrates the first pressing roll of the set operating upon the sole portion of the footwear article;

Fig. 5 illustrates a pair of pressing rolls of the set operating upon the edges of the sole portion 10 of the footwear article;

Figs. 6 and 7 are respectively sectional views of locking mechanisms for the roller carriage and the base upon which it is mounted; and

Fig. 8 is a detailed view of mechanism for 15 applying pressure to the edge pressing rolls shown in Fig. 5.

This invention is illustrated in reference to an apparatus for pressing the built up sole or lower portion of rubber footwear articles. Referring 20 to the drawings the apparatus comprises a conveyor C for supporting the articles and a mechanism M for rolling portions of the articles while they are carried by the conveyor C. Referring to Fig. 1, one of a series of footwear articles in the 25 form of a boot 10 is supported on the conveyor C and its sole or lower portion is carried in rolling contact with a set of rollers comprising a large roller 11 and a pair of smaller edge pressing 30 rollers 12 (Fig. 2) mounted on the rolling mechanism M, which is movably mounted on a track 13 extending along the path of travel of the conveyor C. The mechanism M may be fixed at different points along the track 13 to suitably position the rollers to provide the necessary space 35 along the path to perform the desired operations upon the article before and after it has been operated upon by the rollers 11 and 12.

The boot 10 is lasted on a last 14 mounted on a 40 last support 15 carried by the conveyor C. The axis of the boot leg extends upwards at an acute angle from the horizontal so that the action of gravity retains the last 14 on its support 15 and the bottom portion of the boot is presented in a lengthwise direction to the rolls 11 and 12 which are mounted on a carriage 16 supported on guide rods 17 secured to the base 18 of the mechanism M. The guide rods 17 extend substantially parallel to the axis of the leg of the boot 10 when being operated upon so that the carriage 16 may be moved thereon to or from the conveyor C to adjust the distance between the set of rolls 11 and 12 and the conveyor to provide for the use of lasts of different lengths and to maintain the rolls in alignment therewith at different positions 55

of adjustment. As shown in Figs. 2 and 3 the boot is first contacted by the large roll 11 and then by the edge pressing rolls 12 and a safety stop mechanism 19 is provided to make contact with the boot 10 and stop the movement of the conveyor and thereby prevent injury to the apparatus in the event the carriage 16 and the set of rolls 11 and 12 carried thereby are positioned so close to the conveyor C that the boot may catch on such elements and damage them.

The base 18 is mounted upon rollers 20 cooperating with the top and bottom rails of the track 13 which is secured to a foundation 21. The base 18 may be moved along the track on its rollers and secured to the track by a locking mechanism comprising a handle 22 fixed to a screw threaded rod 23 having oppositely threaded portions 23' (Fig. 7) cooperating with threaded bores in clamping blocks 24 adapted to be clamped by the rod 23 to the top rail of the track 13.

The carriage 16 is movable along guide rods 17 mounted in brackets 25 on the base 18. The guide rods 17 are secured in the brackets 25 by nuts 26 cooperating with the threaded ends of the guide rods and the brackets. The carriage 16 is movable along the guide rods by a pinion 27 fixed on a shaft 28 rotatably mounted in the base 18. The pinion cooperates with a rack 29 formed on the lower portion of the carriage 16 and is operated by a hand wheel 30 secured to the shaft 28. The carriage 16 may be secured in any position along the guide rods 17 by means of a locking mechanism comprising a handle 31 (Fig. 6) keyed to a rod 32 having oppositely threaded end portions 33 cooperating with like threaded bores in clamping blocks 34 which move towards or away from one another by the movement of the handle. The blocks 34 are caused to grip one of the guide rods 17 or release the carriage 16 when the handle 31 is operated.

The set of pressing rolls 11 and 12 is mounted on an upwardly extending post 35 of the carriage 16. The large roll 11 is rotatably mounted in the bifurcated end 36 of a bell crank lever 37 pivoted on a shaft 38 mounted at each end in brackets 39 extending laterally from the post 35. A pair of tension springs 40 are connected between a cross head 41 (Fig. 2) secured to one end of the bell crank lever 37 and a cross head 42 connected to a threaded rod 43 which extends through a bracket 44 on the upright post 35. The rod 43 is movable by a hand nut 45 threaded on the end of the rod 43 and cooperating with the bracket 44 for the purpose of adjusting the amount of pressure exerted by the roll 11 on the bottom portion of the boots 10. A lock nut 46 cooperates with the bracket 44 and the adjusting rod 43 for securing the latter in any position of adjustment. A rod 47 secured to a bracket 48 on the bell crank lever 37 is provided for limiting the movement of the roller 11 towards the path of movement of the boots 10. The rod 47 extends through a bore in the post 35 and a spring 49 positioned between lock nuts 50 on the rod 47 and the post 35 cushions the movement of the roller 11 in opposition to the springs 40.

Referring to Figs. 2, 3, 5 and 8, the edge pressing rollers 12 are rotatably mounted in yokes 51 (Fig. 5) pivotally mounted on rods 52 adjustably secured in brackets 53 by locking nuts 54 cooperating with the threaded ends of the rods 52. The brackets 53 are clamped by screws 53' to pivot shafts 55 oscillatably mounted in brackets 56 extending laterally from the post 35 and secured

thereto by cap screws 57. The cap screws 57 also secure plates 58 to the post 35. Rods 59 pivotally connected at one end to the brackets 53 extend through bores in the plates 58 and are provided with compression springs 60 positioned between the plates 58 and locking nuts 61 on the threaded ends of the rods 59 for the purpose of cushioning the movement of the edge pressing rolls 12 when they leave contact with the boots 10.

Torsion springs 62 (Fig. 8) encircling the shafts 10 55 and cooperating with the brackets 53 are provided for pressing the rolls 12 against the edges of the lower portion of the boots 10. Each spring 62 is positioned between the arm of the brackets 56 and one end of each spring is fixed to one arm 15 and the other end is fixed to a collar 64 secured to the shaft 55 by means of the set screw 65.

The boots 10 travel by the rolling mechanism M in the direction indicated by the arrows A in Figs. 2 and 3 and the safety stop mechanism 19 mounted on an arm 66 extending upwardly from the bottom portion of the carriage 16 is adapted to cooperate with the boots 10 in the event the boots are too close to the mechanism M. The stop mechanism comprises a roller 67 25 rotatably mounted on an arm 68 pivoted on a pin 69 secured in a rocking arm 70 pivoted in a bracket 71 mounted on the arm 66. The rocking arm 70 is provided with a second projection 76 having a set screw 73 adapted to cooperate with an electrical switch 74. A lock nut 75 is provided for adjusting the position of the set screw 73 in reference to the switch. The rocking arm 70 is provided with a second projection 76 having a spring 77 connected between it and the roller arm 68. A second spring 78 is connected between the projection 76 and the arm 66. In the event the carriage 16 is positioned too near the conveyor C the boots 10 will strike against the safety stop roller 67 and operate the arm 40 68 which through the action of the spring 77 operates the rocking arm 70 in opposition to the spring 78 and thereby operates the electrical switch 74 and stops the conveyor C by breaking the electrical connection of the current supply to 45 the motor (not shown) which drives the conveyor.

The conveyor C is mounted upon rollers 79 adapted to travel on a track 80 formed of top and bottom rails similar to the track 13 of the 50 rolling mechanism M.

In the operation of the apparatus the several parts of the rubber footwear are built up on the lasts 14. As shown particularly in side elevation in Fig. 3 and in cross sectional elevation in Fig. 4 the parts to be rolled comprise an insole 81 over which the bottom portion of the upper 82 is turned, a binder sole 83 preferably made of rag and friction rubber stock, and a filler sole. As shown in Fig. 3 the boots 10 pass with their sole portion presented longitudinally to the rollers 11 and 12. The large roller 11 is adapted to roll principally all of the flat portion of the soles and the edge rollers 12 are employed to contact and securely unite the edge portions of 65 the plied up parts.

While the preferred form of the apparatus has been shown and described herein it will be understood that changes in the details may be made without departing from the spirit and scope of 70 the invention as defined in the claims.

Having thus described my invention, what I claim and desire to protect by Letters Patent is:

1. An apparatus for rolling the bottom portion of footwear articles comprising the combi- 75
